UNITED STATES PATENT OFFICE.

WILLIAM J. GOING, OF AMSTERDAM, NEW YORK, ASSIGNOR, BY MESNE ASSIGNMENTS, TO THE KLAUDER-WELDON DYEING MACHINE COMPANY, OF JENKINTOWN, PENNSYLVANIA, A CORPORATION OF PENNSYLVANIA.

DYEING-MACHINE.

1,343,260.

Specification of Letters Patent. Patented June 15, 1920.

Application filed May 8, 1916. Serial No. 96,099.

To all whom it may concern:

Be it known that I, WILLIAM J. GOING, a citizen of the United States, residing at Amsterdam, in the county of Montgomery and

5 State of New York, have invented certain new and useful Improvements in Dyeing-Machines, of which the following is a full, clear, and exact description, such as will enable others skilled in the art to which it ap-
10 pertains to make and use the same.

The invention relates to yarn treating machines, and with respect to its more specific features, to yarn dyeing apparatus.

One of the objects of the invention is the 15 provision of a simple and practical yarn dyeing apparatus in which the yarn is continuously immersed in the dye liquid during the dyeing operation.

Another object of the invention is the 20 provision of practical and efficient means for establishing current of the dye liquor so that all parts of the yarn will be harmoniously dyed.

Another object of the invention is the 25 provision, in apparatus of the character referred to, of rotary yarn sticks, and means coupled therewith, for preventing injury to the machine should the rotation of the sticks be abnormally resisted.

30 Other objects will be in part obvious and in part pointed out hereinafter.

The invention accordingly consists in the features of construction, combinations of elements and arrangement of parts which 35 will be exemplified in the construction hereinafter set forth, and the scope of the application of which will be indicated in the following claims.

In the accompanying drawings forming 40 part of this specification, and wherein similar reference characters refer to similar parts throughout the several views,—

Figure 1 is a side elevation of an embodiment of the invention, showing the vat and 45 operating devices;

Fig. 2 is a plan of Fig. 1;

Fig. 3 is a vertical section of the vat showing its interior arrangement; and

50 Figs. 4, 5 and 6 are detail views illustrating a form of yieldable connection between the yarn sticks and the rotary driving means

therefor; Figs. 5 and 6 being sectional views on the lines $y-y$ and $x-x$, as indicated.

Referring now more specifically to the drawings, the numeral 1 indicates a vat 55 adapted to contain the treating liquid, as dye liquor for dyeing the field of yarn immersed in the vat. A cover for the vat is employed, and in the present embodiment this cover comprises two pairs of foldable cover sections 2 and 3 hinged to each other at 4, the sections 2 being hinged to the ends of the vat at 5 and the sections 3 being provided with a handle or other manipulating device 6. By this construction the section 3 may 60 turn on its hinge 4 to partially uncover the vat, or both sections may turn on hinge 5 to wholly uncover the vat. One pair of the sections fold to the left, in Fig. 3, and the other pair to the right. 70

Within the vat are transverse partitions 7 and 8 spaced from both the top and bottom of the vat and providing chambers 9 and 10 at opposite sides of the vat, in each of which chambers are located means adapted to establish currents of the treating liquid. 75 In the present embodiment each current-establishing device or means comprises rotary propellers having flat vanes 11 extending across the vat near the center of its depth 80 and journaled in longitudinally disposed partitions 12 and 13 forming the sides of the chambers 9 and 10. Each propeller comprises a plurality of propelling wheels provided with the flat vanes 11 referred to and intermeshing in a manner similar to that of a rotary pump, the axes of each pair of 85 wheels being provided with intermeshing gears 14 and 15, so that when one is rotated the other will rotate therewith. The gears 90

14 are connected to rotate with short shafts 16 suitably journaled in a side wall of the vat and provided with bevel gears 17 and 18 meshing with bevel gears 19 and 20 on the longitudinally disposed rotary shaft 21 95 journaled in brackets 22 on the side of the vat. 23 indicates a belt pulley rotatably mounted on the shaft 21 and adapted to be clutched to said shaft for driving the same by any suitable form of clutch having a 100 clutch collar 24, splined to shaft 21, and which latter collar may be manipulated by a

shift lever 25. The numeral 26 indicates a gear wheel rotating with the shaft 21 and meshing with a gear wheel 27 carried by a worm shaft 28, the latter being provided with a worm 29 engaging a worm wheel 30 mounted to rotate on a short shaft 31 supported in a bracket 32 on the side of the vat. 5 33 indicates a clutch element splined to the shaft 31 and having a clutch face adapted to 10 coöperate with a clutch face on the worm wheel 30, so that when the clutch elements of the worm wheel 30 and the collar 33 are in engagement, the shaft 31 will be rotated.

Within the vat, on the shaft 31, is a gear 15 wheel 34 adapted to mesh with the end one of a series of gear wheels 35, the rotation of the wheels 35 being adapted to effect rotation of certain yarn sticks. The series of yarn sticks is adapted to support a plurality, or 20 field of hanks of yarn, within the vat during the dyeing operation. In the present embodiment a plurality of the sticks is supported in the upper portion of the vat on shoulders 36 extending from the partitions 7 25 and 8, the plurality of sticks being connected for support to a frame 37 which may be vertically moved into and out of the vat when the cover is open. Above the frame 37 is supported a series of deflecting plates 38 30 consisting of inclined cross pieces connected at their opposite ends to longitudinal stringers 39 adapted to removably rest on the tops of the partitions 7 and 8. The purpose of the deflecting plates 38 will be more fully 35 explained hereinafter, it being sufficient to note at this point that when the cover is open and the frame 37 carrying the dye sticks is lifted from the vat, these deflecting plates 38 will be lifted therewith. Furthermore, as the plates 38 merely loosely rest in 40 their position in the vat, they may be removed from the vat independently of the yarn stick supporting frame 37.

During the yarn treating operation the 45 propellers, located at opposite ends of the vat and on opposite sides of the field of yarn, are rotated so as to establish currents of the dye liquid downwardly toward the bottom of the vat and inwardly opposite the lower side 50 of the yarn field the flat vanes 11, giving a broad current almost the full width of the vat. In the chambers 9 and 10 are guides 55 40 for directing the dye liquor so that it will readily flow in the desired direction toward the center of the yarn field. The currents produced by the propellers simultaneously 60 flow toward the center of the vat from opposite directions and at their points of confluence the currents naturally tend to flow upwardly through the yarn field. In order 65 to assist and positively direct these oppositely flowing currents through the yarn field and between the propelling means a series of deflecting plates 41 are disposed opposite the lower face of the field, the plates on one side

of the central deflecting plate 42 being inclined in an opposite direction from the plates on the other side thereof. These plates may be fixed in the vat between the liquid propellers as by being supported 70 by the side walls thereof. After flowing through the yarn field the currents meet the similar but oppositely inclined deflecting plates 38 disposed opposite the upper face of the yarn field and branch, the one toward 75 one propeller and the other toward the other, the currents being thus established from the propellers toward each other, thence through the field of yarn and back to the respective current-establishing means or propellers. 80 To assist in the establishment of the current in the general predetermined directions referred to, guides 43 are located in the chambers 9 and 10 above the propellers, being for a purpose similar to that of the 85 guides 40.

Referring now more particularly to Figs. 4, 5, and 6, the numeral 44 indicates a yarn supporting stick, a plurality of these sticks being employed in the present embodiment. 90 Each of these sticks is preferably rectangular in cross section and is rotated during the yarn treating operation. To this end one end of the stick enters a squared socket in a rotatable stick support 45 journaled in a 95 bracket 46 carried by the frame 37, the other end of the stick being supported in any suitable manner for rotation in said frame. The gears 35 in the present embodiment are provided with a clutch element, these gears 100 being chambered so as to provide a ring 46' having an interior circular clutch surface 47 overhanging certain other parts. The numeral 48 indicates a shallow recess in the surface 47, and 49 indicates a coöperative 105 clutch element or shoe bearing on the surface 47 and adapted to frictionally coöperate therewith so as to tend to transmit the rotation of the driven member, or gear 35, to the stick 44. Numeral 50 indicates a yoke having 110 a projection, or tooth 51, which is adapted to be seated in the recess 48, and which at a proper time is thrust into said recess by means of a spring 52 disposed between the yoke and shoe and exerting its stress to press 115 the shoe and the tooth in the direction of the surface 47 of the driven element 35. The rotatable stick support 45 is provided with a transverse channel in which the shoe and yoke above referred to are guided in their 120 movements relatively to each other, this channel being provided with a pair of flat plates 53 and 54 carried by the rotatable member 45 and extending into the chamber of the gear 35, being overhung by the ring 125 46. The plates 53 and 54 engage the lateral flat faces of the shoe 49 and yoke 50, permitting movement of the shoe relative to the yoke transversely of the axis of the stick, and coupling the stick to the yoke and shoe so 130

that rotation of the yoke and shoe may effect rotation of the member 45 and, consequently, of the stick. In order to center the plates 53 and 54 relatively to the surface 47, the 5 member 45 has an extended portion comprising a shaft 55 engaging a centering opening, or bearing 56, in the gear 35, the shaft 55 having oppositely flattened faces 57 engaging the yoke 50 where the yoke straddles the 10 same. Preferably the gear 35 is directly mounted in the bracket 46 bolted to the frame 37 and having a cylindrical bearing 59 in which an extended portion 60 of the gear 35 rotatively bears, and is effectively 15 supported.

By the above described construction it will be observed that the axis of each stick is stationarily positioned during the yarn treating operation, the stick nevertheless being 20 capable of rotating on its axis during the yarn treating operation in order to move the hanks of yarn relatively to the respective sticks so that the dye liquor may have access to the portions of the yarn lying 25 against the sticks.

The operation should be obvious from the foregoing description, but may be briefly described as follows: The covers are thrown back and the frame 37 carrying the yarn 30 sticks on which the yarn field is supported is lowered into the vat, the frames 37 resting upon the shoulder 36. The frame having the deflecting plates 38 is placed in position opposite the upper face of the 35 yarn field and the cover is closed. The pulley 23 being driven from a suitable source of power, is clutched to the shaft 21 by throwing the shift lever 25. Thereupon the propellers and the worm wheel will be 40 caused to rotate. Currents of dye liquor will be established simultaneously from the propellers downwardly and toward each other opposite the lower face of the yarn field, thence through the yarn field, and 45 thence back to the propellers, the deflecting plates 38 and 41 assisting in such establishment. The yarn sticks will be slowly rotated so that the parts of the yarn hanks in contact therewith will eventually come in 50 free and unobstructed contact with the dye liquor, and after a proper length of time the operation of dyeing will be completed, whereupon the covers may be thrown back and the frame 37 lifted by any suitable 55 means to carry the hanks of yarn out of the dye liquor, this lifting also carrying the deflecting plates 38 therewith if they have not previously been removed. Should the yarn become entangled, or if for any other reason 60 normal rotative movement of the sticks be resisted, the friction clutch connection between the gears 35 and the sticks will yield, and the gears may continue to rotate under the driving power without further rotative 65 movement of the sticks. The shallow re-

cess 48 co-operating with the tooth 51 of the yoke 50 forms a sufficient frictional connection between the gear 35 and the stick support 45 to cause the support 45 and the stick therein to be effectively rotated during 70 the operation of dyeing, and abnormal resistance to rotation of the stick will cause the tooth 51 to escape from the recess 48 and permit it to remain stationary while the gear 35 continues to rotate under the influence of the power. The dye liquor flows 75 gently upward through the yarn field and has a tendency to uphold the hanks, causing the bight of yarn over the sticks to spread somewhat so that the dye liquor may come 80 into contact with more of the yarn closely adjacent the stick than it would if this expanding were absent. This expanding, however, when the hanks of the field are closely associated, may result in entanglement of one hank with another, so as to obstruct rotation of the sticks, in which case the connection between the sticks and the driving means will yield, the sticks thereafter remaining rotatively at rest though 90 the driving means continues to operate.

Thus by the above described construction are accomplished, among others, the objects hereinbefore referred to.

As many changes could be made in the 95 above construction and many apparently widely different embodiments of this invention could be made without departing from the scope thereof, it is intended that all matter contained in the above description 100 or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween. 110

Having described my invention, what I claim as new and desire to secure by Letters Patent is:

1. In a yarn treating machine, in combination, a vat to contain the treating liquid, 115 means adapted to support therein a field of material to be treated, means at opposite sides of said field adapted to establish currents of the liquid toward each other, opposite said field, and means adapted to deflect said currents through said field. 120

2. In a yarn treating machine, in combination, a vat to contain the treating liquid, 125 means adapted to support therein a field of material to be treated, means at opposite sides of said field adapted to establish currents of the liquid toward each other, opposite said field, and means adapted to deflect said currents through said field between said current establishing means. 130

3. In a yarn treating machine, in combination, a vat to contain the treating liquid, means adapted to support therein a field of material to be treated, means at opposite 65 sides of said field adapted to establish currents of the liquid toward each other, opposite said field, means adapted to deflect said currents through said field between said current establishing means, and means opposite 70 said field and said deflecting means adapted to deflect said currents toward said current establishing means.
4. In a yarn treating machine, in combination, a vat to contain the treating liquid, 75 means adapted to support therein a field of material to be treated, means at opposite sides of said field adapted to establish currents of the liquid toward each other, and means at opposite sides of said field and 80 between said current establishing means adapted to deflect said currents through said field and back toward the respective current establishing means.
5. In a yarn treating machine, in combination, a vat to contain the treating liquid, 85 means adapted to support therein a field of material to be treated, means at opposite sides of said field adapted to establish broad currents of the liquid toward each other, and means at opposite sides of said field adapted to deflect the currents through said field. 90
6. In a yarn treating machine, in combination, a vat to contain the treating liquid, 95 means adapted to support therein a field of material to be treated, means at opposite sides of said field adapted to establish broad currents of the liquid toward each other, inclined plates opposite one side of said field in the path of said currents adapted to deflect the currents through said field.
7. In a yarn treating machine, in combination, a vat to contain the treating liquid, 100 means adapted to support therein a field of material to be treated, a series of inclined deflecting plates opposite said field, some of said plates being inclined in an opposite direction to others, and means adapted to establish currents of said liquid against said deflectors. 105
8. In a yarn treating machine, in combination, a vat to contain the treating liquid, means adapted to support therein a field of material to be treated, a series of inclined deflecting plates opposite said field, some of said plates being inclined in an opposite direction to others, and means adapted to establish currents of said liquid against said deflectors from opposite directions. 110
9. In a yarn treating machine, in combination, a vat to contain the treating liquid, means adapted to support therein a field of material to be treated, a series of deflecting plates opposite opposite sides of said field, and means adapted to establish a current of the liquid relative to said plates and field, 115 said plates on one side being inclined to deflect the current through said field, and on the other side to deflect the current toward said current establishing means. 120
10. In a yarn treating machine, in combination, a vat to contain the treating liquid, means adapted to support therein a field of material to be treated, and liquid propellers at opposite ends of the vat adapted to establish currents of the liquid simultaneously toward the center of the vat. 125
11. In a yarn treating machine, in combination, a vat to contain the treating liquid, means adapted to support therein a field of material to be treated, chambers on opposite sides of the field of material, a liquid propeller in each chamber, and guides leading from said chamber toward opposite sides of the yarn field and communicating with the vat space intermediate said chambers. 130
12. In a yarn treating machine, in combination, a vat, a support for a plurality of yarn sticks removable from said vat, and current deflectors removable with said support. 135
13. In a yarn treating machine, in combination, a vat to contain the treating liquid, means adapted to support therein a field of material to be treated, and means adapted to cause flow of the treating liquid in said field, comprising devices adapted to establish currents of the liquid toward each other from opposite sides of said field. 140
14. In a yarn treating machine, in combination, a vat to contain the treating liquid, means adapted to support therein a field of material to be treated, and means adapted to cause flow of the treating liquid in said field, comprising devices at opposite sides of said field adapted to establish currents of the liquid toward each other from opposite sides of said field. 145
15. In a yarn treating machine, in combination, a vat to contain the treating liquid, means adapted to support therein a field of material to be treated, and means adapted to cause flow of the treating liquid in said field, comprising devices adapted to establish currents of the liquid toward each other along a side of said field from opposite sides of said field. 150
16. In a yarn treating machine, in combination, a vat to contain the treating liquid, means adapted to support therein a field of material to be treated, and means adapted to cause flow of the treating liquid in said field, comprising devices at opposite sides of said field adapted to establish currents of the liquid toward each other from opposite sides of said field. 155

liquid toward each other along a side of said field from opposite sides of said field.

17. In a yarn treating machine, in combination, a vat to contain the treating liquid, means adapted to support therein a field of material to be treated, and means adapted to cause flow of the treating liquid in said field, comprising devices adapted to estab-

lish broad currents of the liquid toward each other from opposite sides of said field. 10

In testimony whereof I affix my signature in the presence of two witnesses.
